UNITED STATES PATENT OFFICE.

REGINALD A. FESSENDEN, OF WASHINGTON, DISTRICT OF COLUMBIA, ASSIGNOR TO
THE NATIONAL ELECTRIC SIGNALING COMPANY, OF PITTSBURG, PENNSYLVANIA,
A CORPORATION OF NEW JERSEY.

METHOD OF ELECTRIC SIGNALING.

962,014.

Specification of Letters Patent. Patented June 21, 1910.

Application filed January 9, 1905. Serial No. 240,268.

To all whom it may concern:

Be it known that I, REGINALD A. FESSENDEN, a citizen of the United States, residing at Washington, District of Columbia, have 5 invented a certain new and useful Method of Electric Signaling, of which the following is a specification.

My invention relates to receivers for signaling by currents or electro-magnetic 10 waves and has for its object a construction wherein a substance is changed as to one or more of its characteristics by the action of currents or electro-magnetic waves and the changed portion is caused to leave the point 15 of change and after leaving such point produces or controls the production of an indication.

It is a further object of the invention to provide for the formation of a constricted 20 conducting fluid path and for the interruption of such path by a change in the fluid, such interruption causing or controlling the production of an indication, all as herein-after more fully described and claimed.

5 In the accompanying drawing forming a part of this specification Figure 1 is a sectional elevation of a form of receiver embodying my improvement; Figs. 2 and 3 are similar views illustrating modified arrangements of receiving and indicating circuits.

In the practice of my invention the vessel 1 which is preferably glass has its upper and lower portions connected by a constricted 5 portion 2 through which a movement of the substance employed, as for example a 20% solution of nitric acid, may be established. In the construction shown this movement of the liquid, which is for the purpose of causing the portion of the liquid acted on by the electro-magnetic waves to pass through the constricted portion, is produced by the flow of liquid from an elevated receptacle 3 connected by a tube 4 to the lower portion of the vessel 1. An outlet from the upper portion of the vessel is formed by the tube 5 provided with a valve 6 for regulating the rate of flow of liquid through the constricted portion 2. Terminals 7 and 8 of a local circuit which includes an indicating mechanism 9 and a battery 10, are so located that the liquid, especially that portion forming the constricted conducting path, will form a part of the local circuit.

Two terminals 11 and 12, one small and 55 the other preferably larger, are so arranged with reference to the constricted portion 2 that the movement of the substance in the vessel 1 will be from the small terminal 11 to and through the constricted portion 2. 60 These terminals may be directly or indirectly connected to the receiving conductor.

On the passage of a current between the terminals 11 and 12 a portion of the substance contained in the vessel 1 will be 65 changed as to one or more of its characteristics, *e. g.* if the substance be electrolyzable, a bubble will be formed at the fine terminal 11. The portion of the substance thus changed moves or is caused to move away 70 from the fine terminal and so act upon the constricted conducting path as to produce a change in the current flowing through the local circuit. In the case of electrolytic action the bubble will float or be carried by 75 the movement of the liquid through the constricted portion 2, and thereby breaking the local circuit or so reducing the constricted conducting fluid path as to produce a material reduction of current flowing through 80 such path. As will be readily understood the movement of the portion of the substance acted on, as for example the movement of bubbles from the fine terminal, may be observed or the movement of the changed 85 portion may control a local circuit containing an indicating mechanism.

Electrolysis which includes the evolution of gas is not ordinarily produced by alternating currents because when the electrodes 90 are large the film of oxygen gas produced during the passage of the positive half of the current wave produces only a thin coating on the electrode, and this film does not contain a sufficient quantity of gas to enable 95 it to form bubbles and to float up from the electrode. Consequently on the negative half of the current wave passing and evolving hydrogen the hydrogen combines with the oxygen, and as a consequence at the end 100 of each complete wave the original amount of liquid is reproduced. Should, however, either one or both terminals be made so small that there is a large amount of gas per unit of area of the electrode, the gas 105 will not exist in the form of a thin sheet but in the form of a thick layer whose buoyancy will be such that it will break away

from the electrode and float upward. When this is the case the gas evolved during the positive half of the wave will not be in contact with the electrode when the negative half passes, and consequently will not recombine again to form the liquid. During the negative half of the wave consequently the hydrogen gas will be evolved which in turn will float away and the result is that 10 both oxygen and hydrogen will be evolved and the solution will be electrolyzed. Hence when electrolyzable substances are employed the terminal 11 should be made sufficiently fine to permit of electrolysis by the 15 alternating currents produced by electro-magnetic waves.

By making the surface sufficiently small, even the small amount of current flowing at the very beginning of the half wave may be 20 sufficient to crowd all the rest of the gas evolved during the main part of the wave away from the electrode so that practically the whole of the alternating current is effective in producing electrolysis.

25 The amount of hydrogen gas evolved from the fine terminal will not generally mean more than the amount of oxygen and in the figure shown both gases will be carried upward by the current of liquid and at some 30 period of time will form a bubble as shown in the constricted portion 2. When this bubble occupies the position shown the circuit of the local battery 8 will be totally or partially obstructed and an indication will 35 be produced by the indicator 9.

In addition to the gas evolved directly by electrolysis, gas may be evolved by the heating effect of the alternating current waves on the fluid in case the fluid contains a gas. 40 This will also float upward at the same time and will assist to produce an indication.

A receiver of the type herein described is shown connected so that there will be a constantly flowing current between the electrodes 45 7 and 8 and a constant evolution of gas which will produce a constant amount of obstructions in the constricted portion 2. When the currents produced by the electro-magnetic waves flow between the terminals 50 11 and 12, additional gas will be evolved and a change will take place in the amount of obstructions in the portion 2. This change of obstruction will cause a change of current from the local battery 10 and this change of 55 current may be made to effect the indicator 9. Fig. 2 shows a method of connecting the receiver herein shown, 13 being the vertical grounded at *a*, 14 and 15 being primary and secondary of the transformer, the receiver 60 constructed as described is placed in a tuned circuit containing the coil 15 and condenser 18, 9 being the indicating mechanism and 10 the local battery.

In Fig. 3 is shown an arrangement of 65 circuits whereby the liquid and the terminals

11 and 12 form a receiver arranged in operative relation to the receiving conductor 13 and also in a tuned local circuit including coil 15 and condenser 18 with the indicator 20. This circuit is preferably closed as 70 shown. In addition to this local circuit a second local circuit similar to that shown in Figs. 1 and 2 may be used.

While I have shown and described with some particularity apparatus applicable to 75 the practice of my improved method, no claim is made herein to such apparatus as the same forms the subject-matter of an application Serial No. 294,929, filed January 6th, 1906.

80

I claim herein as my invention—

1. In the art of signaling by electromagnetic waves, the method which consists in changing the physical state of a liquid conductor by passing electromagnetic currents 85 therethrough, moving the changed portion of the liquid by reason of its changed condition, and producing an indication by reason of variation in the resistance of the liquid conductor due to the changed condition of 90 said portion, substantially as described.

2. In the art of signaling the method herein described which consists in changing the physical state of a portion of a substance by the action of electro-magnetic waves causing 95 such changed portion to move away from the point of change and thereby effecting a change in the current of a local current in said changed substance.

3. In the art of signaling the method herein described which consists in causing a current to flow through a local circuit, producing a change by the action of electro-magnetic waves in the physical state of a portion 10 of a substance forming a part of the local circuit and causing the changed portion of the substance to move from the point of change and thereby vary the current in the local current in said changed substance.

4. In the art of signaling the method herein described which consists in causing a current to flow through a constricted conducting fluid path and producing by the action of electro-magnetic waves an interruption of 11 the flow of current through said path.

5. In the art of signaling the method herein described which consists in causing a current to flow through a constricted conducting fluid path producing a change in a portion of the fluid at a point outside of the 1 constricted path and causing the changed portion to move into the constricted path and thereby vary the current flowing there-through.

6. In the art of signaling the method herein described which consists in causing a current to flow through an electrolyzable substance, electrolyzing a portion of said substance by a current produced by electro-magnetic waves and utilizing motions of the 1

electrolyzed portion to vary the said first current.

7. In the art of signaling the method herein described which consists in electrolyzing a portion of a substance by the action of electro-magnetic waves and utilizing such electrolyzed portion in a new position to produce a signal or indication by its consequent movement.

10 8. In the art of signaling the method herein described which consists in electrolyzing a portion of a liquid by the action of electro-magnetic waves and moving and utilizing the electrolyzed portion to produce 15 a signal or indication by its change of position.

9. In the art of signaling the method herein described which consists in producing a bubble in a body of liquid by the action of 20 electro-magnetic waves and utilizing the movement of said bubble to produce a signal or indication.

10. In the art of signaling the method herein described which consists in causing a 25 liquid to flow through a constricted channel, producing a bubble in said liquid by the action of electro-magnetic waves and causing said bubble to move into the constricted path.

11. The method of electric signaling 30 which consists in passing a current through a substance so as to change the physical state of part of the substance, moving the changed part away from its initial position and producing a signal by reason of altered 35 conductivity in the circuit due to the changed position of said part.

12. The method of electric signaling which consists in passing the current through a liquid to decompose part of it 40 and form bubbles, moving the said bubbles away from the point of production, and effecting an indication by reason of the motion of said bubbles.

13. The method of signaling which consists in passing electro-magnetic waves through a liquid to create bubbles, causing the bubbles to move through the liquid, and operating an indicating instrument by the effect of such motion of the bubbles through 50 the liquid, substantially as described.

In testimony whereof, I have hereunto set my hand.

REGINALD A. FESSENDEN.
